WAVE MOTOR

Filed Jan. 26, 1929

UNITED STATES PATENT OFFICE

WILLIAM R. MOBLEY, OF MIAMI, FLORIDA

WAVE MOTOR

Application filed January 26, 1929. Serial No. 335,236.

This invention relates to wave motors and it is an object of the invention to provide a device of this character wherein the force of the waves is converted into power for practical purposes.

It is also an object of the invention to provide a motor of this kind comprising a member possessing a certain degree of buoyancy which rises and falls with the waves, together with means operated by said member during its movements for creating energy for practical purposes.

An additional object of the invention is to provide a motor of this kind comprising a member possessing a certain degree of buoyancy to maintain the same substantially in submergence at the water line portion, together with means for causing said member to rise and fall with the waves in substantially a fixed path of travel and also means for creating for practical purposes a source of energy resulting from the rise and fall of said buoyant member.

The invention consists in the details of construction and in the combination and arrangement of the several parts of my improved wave motor whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawings, wherein:—

Figure 1 is a view partly in side elevation and partly in section illustrating a wave motor constructed in accordance with an embodiment of my invention;

Figure 2 is a view in top plan of the structure as illustrated in Figure 1 with the buoyant body omitted, the compressors and the parts directly associated therewith being disclosed in somewhat a diagrammatic manner.

As disclosed in the accompanying drawings, S denotes a tubular standard of requisite dimensions and which is adapted to have

its lower portion properly set within the bed of the body of water with which the motor is employed. The wall of this standard S for a desired distance therealong is provided with a slot 1.

Freely disposed through this slot 1 is an arm or extension 2 carried by the lower end portion of an elongated member 3 extending upwardly within the standard S and terminating at all times at a desired distance thereabove. This extension or arm 2 is laterally disposed with respect to the member 3 and the portion of the arm or extension 2 exteriorly of the standard S is secured to the upper central portion of a buoyant body B.

This body B is preferably spherical in form and hollow and the interior of the body B, preferably at a point above its horizontal center, is intersected by a partition 4 whereby the interior of the body B is divided into two chambers 5 and 6. The body B at diametrically opposed points and also the central portion of the partition 4 are provided with the aligning openings 7 of such diameters whereby the body B may be engaged upon the standard S in a manner to permit said body B to have free up and down movement with respect to the standard S when the motor is in assembled and applied position. These openings 7 are continued through the sleeves 8 bridging the spaces between the partition 4 and the upper and lower central portions of the body B, or those portions provided with the openings 7.

The lower chamber 5 in the present embodiment of my invention constitutes a dead air chamber although it is to be understood that if preferred said chamber may be filled with any suitable gas or the like of a specific gravity less than that of the water. The upper chamber 6 is adapted to have placed therein a suitable ballast medium 9 which may be of any desired character, preferably water, so that the buoyancy of the member B can be so controlled or regulated as to cause the same to be substantially in submergence at all times at the water line yet readily moving up and down under the influence of the wave action. The upper portion of the body B is provided in its wall with a filler opening 10 in

communication with the chamber 6, said opening being normally closed by a plug 11 or its equivalent.

Mounted upon the upper end portion of the standard S is a platform P of desired dimensions and suitably placed upon the platform P are air compressors C of any desired number and which are in desired driven connection with a shaft 12 mounted upon the platform P. Suitably fixed upon this shaft 12 is a pinion 14 which is constantly in mesh with the rack 15 extending a desired distance along the upper portion of the member 3 hereinbefore referred to so that as this member 3 is vertically reciprocated upon rise and fall of the body B with the waves, the shaft 12 will be rotated to effect the desired operation of the compressor C, such operation occurring during both strokes of the member 3.

Any suitable means, as at 16, may be provided to maintain the rack 15 constantly in mesh with the pinion 14.

The compressors employed in connection with my improved motor are of a type including reciprocating pistons and it will, therefore, be obvious that each compressor will be effective irrespective of the direction in which the shaft 12 may rotate.

It is also to be noted that in connection with this motor the body B also serves to maintain at all times the requisite balance and which is of particular importance at the period the shaft 12 changes its direction of rotation as by so acting this body B substantially eliminates any loss in the working efficiency of the compressor C.

It is to be understood that the standard S is of such length as to assure the platform P being positioned at all times above the surface of the water.

From the foregoing description it is thought to be obvious that a wave motor constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as herein-after claimed.

I claim:—

1. In a wave motor mechanism, a buoyant body for the actuation thereof, consisting of a casing adapted to exclude fluid and having a horizontal partition separating the casing into two compartments, the upper compartment being substantially filled with a ballast above the surface of the water, said ballast being of substantially the same weight as the

water displaced by one half of the cubic capacity of said casing.

2. In a wave motor mechanism, a buoyant body for the actuation thereof, consisting of a casing adapted to exclude fluid and having a horizontal partition dividing it into two compartments, the upper compartment being smaller than the lower compartment and adapted to receive a ballast which is substantially equal in weight to that of the water displaced by the casing when floated, at which point said partition is substantially in the plane of the surface of the water.

In testimony whereof I hereunto affix my signature.

WILLIAM R. MOBLEY.
